UNITED STATES PATENT OFFICE.

CLIFFORD ETCHES WINBY, OF SUTTON, ST. HELENS, ENGLAND.

LOCOMOTIVE AXLE-BOX.

1,311,734.

Specification of Letters Patent. Patented July 29, 1919.

Application filed October 7, 1916. Serial No. 124,359.

To all whom it may concern:

Be it known that I, CLIFFORD ETCHES WINBY, a subject of the King of England, residing at Sutton, St. Helens, in the county of Lancaster, England, have invented new and useful Improvements Relating to Locomotive Axle-Boxes, of which the following is a specification.

This invention has reference to locomotive axle-boxes, and more particularly to the "sponge-box" of same, that is the box which comes under the journal of the axle, and generally fits within depending side portions of the upper bearing; and it further relates to such boxes which have removable plates or parts for obtaining access to the lubricant holding part, or removable lubricant boxes.

The sponge box in practice is generally filled with cotton "waste" or the like which absorbs and holds oil, which usually passes to it from the upper bearing, into which the lubricant is introduced.

At present, in most locomotives, the wheel comes close up to the outside of the axle box and sponge box; while on the inside of the bearing, a collar or shoulder on the shaft, or the crank in the case of a driving axle, comes, so that access to this box either from the outside or from the inside is not available; and in order to obtain access to it for inspection or otherwise, it is necessary to lift the locomotive up and lower the box.

The object of the present invention is to provide improvements in axle boxes which will enable access to be more readily had to the axle journals and sponge boxes from inside the box, without this necessity of lifting the locomotive; and according to this invention this is accomplished by constructing the sponge-box with a removable part arranged and adapted as hereinafter explained with reference to the drawings, that it can be readily taken off; and when removed access to the interior of the box, and thereby to the journal surface is had, so that this journal can be examined, and the box repacked with waste or the like without lifting the engine or taking down various parts and connections, as well as the bearing parts proper.

In the drawings which illustrate this invention, Figure 1 is an internal face view of the axle bearing sponge-box; Fig. 2 is a lon-

gitudinal section through the box; and Fig. 3 is a plan. Figs. 4, 5 and 6 are corresponding views to Figs. 1, 2 and 3, showing a modification; and Fig. 7 shows a complete axle box bearing.

Referring to the drawing, 1 is the outside wall of the box, 2 are the side walls, and 3, the inside wall, which is the removable part referred to. These outer and inner end walls or parts 1, and 3 are curved correspondingly with the axle in connection with which the box would be used, and the edges lie close up to the surface of the journal; and in the case of a driving axle box, the crank of the locomotive will lie close to the inner wall 3; whereas in the case of another axle, the shoulder or collar on the inside of the journal will lie just outside the wall 3; and thus, ordinarily, it is impossible to obtain access in any way with the journal which lies inside the sponge box, nor to the interior of the box.

In the form shown in Figs. 1 to 3, the plate 3 has down its side, and along its lower edge, a thin flange 4; and the lower portion 3^x of this end wall of the box, which lies below the bottom 5, is recessed inward, the bottom of the recess being flush with the surface of the sides 2; so that when the plate 3 is in position, its outer surface is flushed with the general plane and surface of the inside wall 3^x; and this surface will also be flush with the surface of the axle bearing proper, as usual.

Normally, the plate 3 is attached to the box edges of the sides 2, and to the lower walls of 3^x, and held in position by screwed stud bolts 6 which pass through the flanges 4, and screw into tapped holes in the walls 2 and 3^x.

The heads of the studs 6 are made thin, so that in the case of the application to a driving axle bearing of the locomotive, the path of the crank will be clear of the heads. Or the screws 6 may be countersunk into the plate 3.

A thin leather or light washer or insertion 7 is provided between the inner surface of the flanges 4, and faces of the bottom 5 and sides 2, against which it fits, so that when the plate 3 is screwed up, the box will be oil tight.

The holes 8 in the side walls 2 are those through which the usual pins are passed;

which holds the sponge box up in the side portions of the bearing box proper, and against the journal.

When it is required to gain access to an axle shaft journal, and the interior of a sponge box, the studs 6 are withdrawn, and when removed the lower edge of the lower flange 4 is pulled away from the box; and when the bottom edge of the plate 3 at the 5 inside corner is clear of the bottom 5, the plate 3 can be dropped out of the way, and so the whole of the interior of the box and the surface of the journal can be got at. After inspection the old waste having been 10 removed, a fresh packing of waste or the like can be freely introduced and pressed into the box, so that it will fill the whole of its interior, and will bear on the under side of the shaft; and when the box is sufficiently packed, the plate 3 can be lifted up 15 and placed in position again, and the studs 6 screwed up; the insertion 7 making the necessary liquid-tight joint.

Ledges marked 10—shown in Figs. 2 and 25 3—may be furnished in the box, and flat springs 16 arranged across the bottom and resting on these ledges at their ends, may be used. These springs would be suitably spaced apart so that when the packing is 30 pressed and packed into the box when the end plate 3 is off, the springs, being light, will be put under strain; and after the plate 3 is fastened up, their reaction will press and keep the packing or waste on to the 35 under surface of the axle journal. The spaces between the flat spring will be such as will allow the waste to project down into space in the box bottom beneath them, which when the box is properly charged 40 with lubricant will act as a reservoir. The packing will thus be fed with oil and keep wet, and so will continuously transfer oil to, and keep the surface of the axle journal well oiled and lubricated.

45 In Fig. 7, the bearing proper on which the journal of the axle rests is marked 16, and 17 are the usual pins passed through the side plates of this bearing, and the sponge box lower part, which keeps these 50 parts together. 18 is the horn-frame of the locomotive in which the whole bearing and sponge box work up and down in, and 19 is the tie plate, which secures or ties the two ends of the horn-frame together.

55 In the modification in Figs. 4 to 6 the removable part 3 has connected with or formed in one with it, other parts constituting a container—namely sides 11 and 12, and bottom 13,—which fit within and practically fill the interior of the sponge box; and it is held in place in the sponge box by the screwed stud bolts 6, which pass through the bottom 5 of the sponge box, with their inner reduced ends 6^x projecting 60 up into the container bottom 13; so that

when the studs are in this position, the plate 3 and container, cannot move outward and therefore the end plate 3 is held flush with the face of the sponge box.

Furthermore, this plate 3 and the container, containing the waste or like packing is held in position and pressed upward toward the axle journal by screwing up the studs 6, whereby the annular surface of the set screws lying outside the reduced ends 6^x 75 will lift the container up, and press the packing material or waste in it onto the surface of the journal. In this case also, the spring grid bottom arrangement above described may also be used within the container.

When the container is pressed up by the set screws 6, the upper convex edges of the plates 3 and 12, will come close to the journal; and when they are lowered, it is so arranged that these edges will come below the level of the shoulder of the axle journal or the crank when in its upper position, as the case may be, in which condition the plate 3 and container can be withdrawn 80 laterally.

To enable the plate 3 of container to be removed, a recess 14 is provided in the bottom plate 3^x, and a recess 15 is provided in the bottom of the plate 3 so that a lever or 95 the like can be inserted in the opening 14, and its end entered in the recess 15, and the container pressed outward laterally.

The application and use of one or other modification of the invention in connection 100 with any particular locomotive bearing, will depend upon the structure conditions, as will be understood by locomotive engineers and others; but one or the other can be used in connection with any driving axle 105 or any non-driving axle, in any case.

What is claimed is:

1. In a locomotive axle box, a sponge box having a bottom, sides, and end, and one end formed open, said bottom being provided with a recess at the open end; a tray removably mounted within the sponge box and adapted to be removed therefrom through the open end, said tray having openings formed in the lower surface of its bottom and provided at its outer end and in its bottom with a notch adapted to be placed at the recess; and bolts having screw threaded engagement with the bottom of the sponge box and provided at their upper 115 ends with smooth extensions which enter the openings in the bottom of the tray.

2. In a locomotive axle box, a sponge box having a bottom, sides, and end, and having one end formed open, said bottom being provided with a plurality of screw threaded 125 openings; a tray arranged within the sponge box and adapted to be removed therefrom through the open end of the sponge box, said tray having recesses 130

formed in the lower surface of its bottom; and bolts having screw threaded engagement within the screw threaded openings and having smooth extensions projecting 5 into the recesses of the tray and adapted to be removed therefrom.

3. In a locomotive axle box, the combination of a sponge box 1, with a wall at the outside end and each side, and open at 10 the inside end; a removable tray part having walls 3 and 12, and side walls; and hold-

ing and adjusting screws 6 through the bottom of the box 1; substantially as set forth.

In testimony whereof I have signed my 15 name to this specification in the presence of two subscribing witnesses.

CLIFFORD ETCHE WINBY.
